WATER CRAFT

Theodore F. Thompson, Des Moines, Iowa

Application November 12, 1940, Serial No. 365,353

5 Claims. (Cl. 115—20)

This invention relates to water vehicles, and has for its principal object the provision of a novel type of water craft in which the water displacement is reduced to a minimum, the power utilized in propelling the craft forward being so applied that in operation at high speeds there is little or no submersion of any portion of the craft beneath the surface of the water.

More specifically, the invention relates to that type of water vehicle having a generally spherical body within which may be located a motor or other propulsion unit, the motor being operatively connected with the body to rotate the latter about a diametrical axis horizontal to the surface of the water, so that the body literally rolls over the surface during operation. Preferably the external surface of the body is provided with an annular keel to maintain the intended direction of movement of the vehicle and increase the stability thereof, and is further formed to provide propulsion surfaces for engagement with the water, these surfaces being shaped so as to impart combined forward and upward movement to the body on submersion, and so as to emerge from the water with a minimum of resistance.

A further object of the invention is the provision, in a vehicle of the character described, of a hollow body within which is provided a frame for the mounting of a propulsion unit, the body being apertured on the diametrical axis of rotation thereof to permit the extension of the frame exteriorly of the body for connection with stabilizing floats, the floats being so positioned as to resist rotation of the frame about the rotational axis of the body. The invention contemplates that the lateral apertures in the body shall be sufficiently large to permit access to the interior of the body for the purpose of loading passengers or freight therein, closure members being associated with these apertures. It is furthermore contemplated that a substantially closed passenger or freight compartment, supported by the frame, be incorporated in the body, and that a control compartment, also mounted on the frame, be provided forward of the body and exteriorly thereof so as to accommodate a pilot having full control over the operation of the vehicle, the control compartment being disposed and constructed to afford reasonably complete vision to the pilot.

Further objects and features of the invention will be apparent from the following description taken in connection with the accompanying drawings, in which

Figure 1 is a side elevation, partly in section, illustrating one embodiment of my invention;

Figure 2 is a fragmentary horizontal sectional view taken substantially on the line 2—2 of Figure 1;

Figure 3 is a side elevation of the central portion of the structure shown in Figure 1;

Figure 4 is a plan view corresponding to Figure 1; and

Figure 5 is a vertical sectional view taken substantially on the line 5—5 of Figure 1.

In order to facilitate an understanding of the invention, reference will be made to the several embodiments thereof illustrated in the accompanying drawings and specific language will be employed. It will nevertheless be understood that various further modifications of the devices illustrated herein, such as would fall within the province of those skilled in the art to construct are contemplated as part of the present invention.

Referring first to Figures 1 and 4 of the drawings, which represent elevational and plan views respectively of the vehicle, it will be observed that the principal elements of the structure are the spherical body 10, the spherical floats 11, and the connecting frame structure indicated generally at 12. While a truly spherical form is preferable for both the vehicle body and the floats, it is not essential, and while these elements are described for convenience hereinafter as generally spherical, it will be appreciated that it is intended to include within the scope of the language modifications of shape embodying the essential advantages of the structure shown herein but departing substantially from the preferred truly spherical form.

The frame 12 which functions as the connecting structure between the body 10 and the floats 11 extends within the body 10, and is journaled in the latter so as to permit rotation of the body about a substantially horizontal diametrical axis. Thus the shaft 15, supported on and defining this axis, is connected rigidly to depending pairs of arms 16 and 17 and to an upstanding pair of arms 18. Journaled in and extending between the arms of each pair, 16 and 17, are rotatable shafts 19. Each of the shafts 19 carries a gear 20 which is secured to the shaft centrally thereof and each shaft is provided with flanged rollers 21 engaging annular tracks 22 which are supported on the inner periphery of the body 10. The gears 20 mesh with annular racks 25 which are likewise supported on and secured to the inner peripheral wall of the body. A shaft 28, extending between and supported by arms 18, is provided with flanged rollers 29 engaging tracks

22, to complete the mounting of shaft 15 on the horizontal diametric axis of the body 10.

Mounted on and extending between the shafts 19, and disposed adjacent opposite ends of the latter, is a pair of curved arms 30 on which is mounted in any convenient manner a source of motive power, such as the internal combustion engine 32. Mounted on the crankshaft 34 of the engine 32 are a plurality of pulleys 35 which are geared by belts 36 to pulleys 37 mounted on opposite ends of the shafts 19. The pulleys are suitably dimensioned to provide for the driving of the shafts 19 and the gears 20 mounted thereon at any convenient rotational speed. For example, the pulley ratio may be such that the engine and driven shaft speeds have a ratio of 3:2. The speed of rotation of the body 10 is of course further dependent on the relative diameters of the gears 20 and rack 25.

The exterior surface of the body 10 is formed to provide propulsion surfaces for engagement with the water, and in the preferred embodiment of the invention, these propulsion surfaces are afforded by a plurality of transversely extending blades 40 which are rigidly secured to the body adjacent a median vertical plane. It will be noted that each of the blades 40 defines a plane which is so inclined to the body that as the blade enters the water, the forward or propulsion surface thereof exerts a force against the water surface of which the major component is downward, so as to tend to lift the body. As the blade emerges from the water surface, it is substantially normal to the latter and thus little or no resistance is offered by the water to the withdrawal of the blade. The effect of this disposition of the propelling blades is therefore such that the body tends to rise to the surface of the water and to skim over the surface, so that the body offers comparatively little resistance to forward movement. Furthermore, the rotation of the body about a horizontal axis, gives a rolling effect and affords further reduction of resistance to forward movement.

In order that lateral rocking of the body may be minimized, lateral drift reduced, and steering facilitated, the body is preferably provided with an annular keel 42 which is disposed substantially in the median vertical plane of the body. This keel completely surrounds the body and is rigidly secured thereto and may be further secured in any convenient manner to the transversely extending propulsion blades so as to strengthen the latter, for example by welding.

A platform 45, defining a substantially horizontal plane within the body, is secured to the frame 12, for example by rigid connection with the oppositely disposed pairs of arms 16 and 17 which are in turn rigidly mounted on the shaft 15. This platform, together with a generally spherical dome 46 which is mounted thereon and which conforms generally to the internal dimensions of the upper portion of the body, defines a storage space or a passenger compartment, or both, this compartment being indicated generally by the reference character 48.

Since the shaft 15 is journalled in the body by means of the flanged rollers 21 and 29, it is not necessary to provide further supporting bearings for the shaft 15 adjacent the points of emergence thereof from the body at opposite sides of the latter. Consequently, the body may be cut away at opposite sides to provide large apertures 50 affording access to the compartment 48. Closure members 51 may be mounted on the shaft 15 for

sliding movement along the shaft toward and away from the apertures 50, so that the latter may be closed when desired. Any suitable means, not shown, may be provided for displacing the closure members axially of the shaft and for retaining the same in any desired position thereon. The end portions of the shaft 15 are of circular section, so that the closure members may rotate with the body when in aperture-closing position; the central portion of the shaft is preferably non-circular to facilitate rigid attachment thereto of the arms 16, 17, and 18.

The exterior portion of the frame 12 is secured to the outer ends of the shaft 15 in any convenient manner, and the main or supporting structure of the frame may consist of conventional structural elements, for example channel members 54. These channel members, which may be strengthened by transverse structural members in a manner similar to that followed in the construction of automobile frames, extend both rearwardly and forwardly from the points of connection to the shaft 15. Preferably the entire frame is covered by a sheet metal shell 55, which is secured to the structural members of the frame and which completely houses the upper portion of the body 10 and conforms generally to the shape of the latter, so as to function as a hood or fender to prevent the scattering of water by propelling blades. This shell is also preferably shaped so as to minimize wind resistance and may be streamlined in accordance with accepted principles of design. The shell 55, and the supporting structural frame members, may be carried forward of the body to provide an overhanging control cabin indicated generally at 58, this cabin being provided with a door 59 affording access thereto and being liberally supplied with windows 60 giving full vision to the pilot to facilitate control of the vehicle. The usual control mechanism, not shown, is provided within the cabin and suitable control connections are carried rearwardly on the frame 12 to the interior of the body 10 and to a rudder 62 at the rear of the frame. Access for the control connections to the interior of the body can of course be provided through the shaft 15 which may be made hollow for this purpose or may be suitably apertured to permit the passage therethrough of the control elements, so that operation of the motor may be effected from the control cabin 58. Hollow shaft ends are further desirable as providing conduits through which the engine may be supplied with air and water, engine exhaust and water discharged, and ventilation of the interior of the body effected.

A cat-walk 56, supported on the exterior of the body at one or both sides thereof, may afford communication between the apertures 50 of the body and the control cabin 58.

The channel members 54, defining the outline of the exterior portion of the frame 12, converge and may be secured together adjacent the rearward portion of the frame. A transverse shaft 65 is journalled in suitable bearings carried by the channel members, and floats 61 are secured to the ends of the shaft, so that these floats may rotate about a substantially horizontal axis during forward movement of the vehicle, thus reducing the frictional resistance offered thereby to forward movement of the vehicle. The lateral spacing of the floats is sufficient to afford adequate lateral stability to the entire structure, and the floats are of sufficient dimensions to resist the torque imparted to the frame by the

driving engine, the floats thus serving as the reacting elements for the motive power which rotates the body.

Water-craft embodying the principles outlined herein may be highly useful for military purposes. Thus the compartment 48 may be loaded with high explosives, the craft may be driven at high speed toward an enemy craft or other objective, and the explosives ejected from the compartment 48 through the apertures 50 by an attendant within the compartment. The craft may then be steered rapidly away from the site of the explosion. Alternatively, the craft may be loaded with explosives and operated by remote control radio so as to cause the craft to collide with the objective.

If desired, the forward control cabin 58 may be omitted, and the controls housed within the rear portion or tail of the frame structure intermediate the vehicle body 10 and the stabilizing floats 11.

It will be appreciated that the embodiment of the invention shown in the drawings is illustrative only. Various modifications of the details of the structure, not departing from the principles of the invention as outlined herein, are contemplated as part of the invention. It will also be appreciated that various features of the invention, while preferably employed in combination with other illustrated features, may be applied to water vehicles otherwise differing materially from that shown and described herein.

Having thus described the invention, what is claimed as new and desired to be secured by Letters Patent is:

1. In a water vehicle, the combination with a hollow, generally spherical body having peripheral propulsion surfaces, of a frame journalled within said body on a diametrical axis of the latter, a motor carried by said frame, means operatively connecting said motor to said body to rotate the latter about said axis, said frame extending exteriorly of said body, means carried by said frame for engagement with the water to resist rotation of said frame on the application of driving torque to said body, and a control compartment carried by said frame and disposed forwardly of said body.

2. In a water vehicle, the combination with a hollow spherical body having peripheral propulsion surfaces, of a frame journalled within said body on a diametrical axis of the latter, a motor carried by said frame, means operatively connecting said motor to said body to rotate the

latter about said axis, said frame extending exteriorly and rearwardly of said body, laterally spaced floats carried by the rearward portion of said frame, and a hood carried by said frame and encompassing the upper surface of said body.

3. In a water vehicle, the combination with a hollow spherical body having peripheral propulsion surfaces, of a frame journalled within said body on a diametrical axis of the latter, a motor carried by said frame, means operatively connecting said motor to said body to rotate the latter about said axis, a shaft disposed generally on said axis and carrying said frame, said body being provided with apertures to permit extension of said shaft exteriorly of the body and to afford access to the body interior, and closure means for said apertures mounted on said shaft and displaceable thereon toward and away from said apertures.

4. In a water vehicle, the combination with a hollow spherical body having peripheral propulsion surfaces, of a frame journalled within said body on a diametrical axis of the latter, a motor carried by said frame, means operatively connecting said motor to said body to rotate the latter about said axis, a shaft disposed generally on said axis and carrying said frame, said body being provided with apertures to permit extension of said shaft exteriorly of the body and to afford access to the body interior, closure means for said apertures mounted on said shaft and displaceable thereon toward and away from said apertures, and stabilizing means including floats carried by said shafts exteriorly of said body.

5. In a water vehicle, the combination with a hollow spherical body having peripheral propulsion surfaces, of a frame journalled within said body on a diametrical axis of the latter, a motor carried by said frame, means operatively connecting said motor to said body to rotate the latter about said axis, a shaft disposed generally on said axis and carrying said frame, said body being provided with apertures to permit extension of said shaft exteriorly of the body and to afford access to the body interior, closure means for said apertures mounted on said shaft and displaceable thereon toward and away from said apertures, and stabilizing means including floats carried by said shafts exteriorly of said body, said floats comprising spherical members spaced laterally and journalled for rotation on a common axis generally parallel to said body axis.

THEODORE F. THOMPSON.
